(57) **CLAIM**

The ornamental design for a shoulder massager, as shown and described.

DESCRIPTION

FIG. 1 is a perspective view of a shoulder massager showing my design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is bottom plan view thereof;

FIG. 9 is a perspective view showing the shoulder massager in use; and,

FIG. 10 is a front elevational view showing the shoulder massager in use.

The broken lines shown in FIG. 9 and FIG. 10 illustrate environmental structure and form of the shoulder massager which forms no part of the claimed design.
